LAMPHOLDER SET FOR FLUORESCENT LAMPS

James F. Sullivan, Eastchester, N.Y., assignor to
Kulka Electric Corp., Mount Vernon, N.Y.

Filed Mar. 16, 1972, Ser. No. 235,464

Term of patent 14 years

Int. Cl. D13—03

U.S. Cl. D26—1 G

FIG. 1

FIG. 2

FIG. 5

FIG. 3

FIG. 4

FIG. 6

FIG. 7

FIG. 8

FIG. 9

FIG. 1 is a top plan view of one element of a lampholder set for fluorescent lamps showing my new design; FIG. 2 is a front elevational view thereof;

FIG. 3 is a side elevational view thereof;

FIG. 4 is an elevational view thereof from the side opposite to that of FIG. 3;

FIG. 5 is a bottom plan view thereof;

FIG. 6 is a front elevational view of a lampholder constituting the other element of the lampholder set for holding the opposite end of a fluorescent lamp, this lampholder also having the top plan view of FIG. 1;

FIG. 7 is a side elevational view of the lampholder of FIG. 6;

FIG. 8 is an elevational view of the lampholder of FIG. 6, from the side opposite to that of FIG. 7; and

FIG. 9 is a bottom plan view of the lampholder of FIG. 6.

I claim:

The ornamental design for a lampholder set for fluorescent lamps, substantially as shown and described.
